EXERCISING APPARATUS

Ernest J. Boger, Allentown, Pa.

Application September 1, 1938, Serial No. 228,057

2 Claims. (Cl. 272—83)

This invention relates to exercising apparatus.

It is particularly aimed to provide a construction which may be made in cabinet form so as to be portable and in order to occupy minimum space when not in use.

It is further aimed to provide such a construction wherein one of the panels is adapted to be lowered so that the user may impose his weight thereon to securely maintain the structure in position, and further to provide a foldable part which provides seating means for the user and a means to brace all of the parts in a novel manner when unfolded.

It is further aimed to provide such a structure having various elements for attachment of weighted cords, strings or other exercising elements in various positions, so that the user may carry out the maximum number of different exercises usually performed with such elements.

The more specific objects and advantages will become apparent from a consideration of the description following taken in connection with the accompanying drawings illustrating an operative embodiment.

In said drawings:

Figure 1 is a view of the apparatus in folded condition and in perspective;

Figure 2 is a view primarily in front elevation with the front panel removed;

Figure 3 is a detailed section taken on the plane of line 3—3 of Figure 1;

Figure 4 is a view similar to Figure 3 but with the parts in unfolded condition;

Figure 5 is a front elevation of the apparatus in unfolded condition;

Figure 6 is a detailed section taken substantially on the plane of line 6—6 of Figure 4;

Figure 7 is an enlarged detail in elevation showing one of the cam levers engaged with a rod, and

Figure 8 is a cross section taken on the line 8—8 of Figure 7.

Referring specifically to the drawings wherein like reference characters designate like or similar parts, the invention is built in the form of a cabinet generally designated 10 and it has a container section 11 consisting of a main wall 12, parallel walls 13 and parallel walls 14 at the ends thereof, all of such walls being rigidly secured together in any suitable manner. Such cabinet also comprises a panel or closure 15, for said container section 11 and it is hinged to the latter at one of the walls 14 as at 16, so that it may be swung to and from a closed position of Figures 1 and 3 and the open position of Figures 4 and 5.

The structure may be carried or transported by a foldable handle 18, if desired.

Within the cabinet, various hooks are provided for detachable connection of exercising elements thereto, such elements being generally designated 19. These elements 19 are conventionally shown since they may be springs, cords with weights thereon or any equivalent or substitute. These elements preferably have eyelets 20 at attaching ends and preferably have handles 21 at the other ends. Such eyelets for example, may be applied to a pair of hooks 22 on the side walls 13 as shown in Figure 2. They may selectively be applied to a pair of hooks 23 on one of the end walls 14 as also shown in Figure 4. Selectively, the same eyelets 20 may be applied to an upper set of hooks 24 or a lower set of hooks 25, both fastened to the wall 12. In addition, a pair of hooks 26 may be applied to the panel 15 for attachment of said exercising devices 19 thereto.

It will be realized that the various hooks enable an operator who usually either stands or is seated on the panel 15, to attach the exercising elements at practically any preferred position, in order to exercise therewith in the same manner as in a gymnasium.

In order to permit the invention to function efficiently, it will be realized that when the panel 15 is lowered as in Figure 4, it must be effectively braced or in rigid relation with the section 11. To this end, a pair of brace rods 27 are employed and are pivoted as at 28 to the panel 15. The said rods slide through and are guided by loops 29 of brackets 30 which are suitably fastened to the sides 13. Pivoted to each loop 29 as at 31 is a lever 32 having on each side thereof a cam 33. Normally the cams 33 are disposed out of the path of sliding of the rods 27. However, when the rods are in the position of Figure 4, with the parts unfolded, cams 33 are moved into frictional clamping and retaining engagement with the rods through the turning of the levers 32.

In order that the operator, when desired, may be seated, a collapsible seating structure generally designated 34 is employed. To this end, a bat-ten 35 is rigidly fastened within the section 11 and has a bar 36 pivoted thereto as at 37. Such bar 36 at one end carries a suitable seat 38 for the operator. A leg or struts 39 are fastened together and manipulated by a rod 40 and the struts are pivoted as at 41 to the bar 36 adjacent the seat 38. In addition, the struts 39 have lugs or dowels 42 which are detachably applicable in openings or recesses 43 in the panel 15 as shown in Figure 4. It will be realized, as shown 55

in Figure 3 to advantage, that the bar 36 and strut 39 may be folded into parallelism for location within the cabinet or section 11 when the cabinet is folded.

5 Various changes may be resorted to provided they fall within the spirit and scope of the invention.

I claim as my invention:

1. Apparatus of the class described comprising 10 a container section adapted for connection of exercising apparatus therein, a closure section pivoted thereto at one end, means to rigidly secure the closure section and container section together at right angles to each other so that the closure section and one end of the container section may rest on a floor, a bar pivoted within the container section closer to the top than to the bottom and short of the back wall thereof and being of a length to extend 15 outwardly over the closure section to form a seat for an exerciser whose weight maintains the apparatus in place, strut means pivoted to the bar and disposable at its lower end on said closure section, said bar and strut means being foldable together with the strut means at the rear of the bar and disposable 20 within the container section.
- 25

2. Apparatus of the class described comprising a container section adapted for connection of exercising apparatus therein, a closure section pivoted thereto at one end, the closure section and container section being disposable at right angles 5 to each other so that the closure section and one end of the container section may rest on a floor, a bar pivoted within the container section closer to the top than to the bottom and short of the back wall thereof and being of a length to extend 10 outwardly over the closure section to form a seat for an exerciser whose weight maintains the apparatus in place, strut means pivoted to the bar and disposable at its lower end on said closure section, said bar and strut means being foldable 15 together with the strut means at the rear of the bar and disposable within the container section, said strut means and closure section having interengaging means, a brace member pivoted to the closure section, a bracket on the container section having a loop guiding the brace member, and a clamp member pivoted to the bracket and engageable with the brace member.

ERNEST J. BOGER. 25
